CLAIM

The ornamental design for a tool tray assembly, as shown and described.

DESCRIPTION

FIG. 1 is a perspective view of a tool tray assembly showing our new design, the tool tray assembly having a tool tray and two storage boxes nested in recesses in the tool tray;

FIG. 2 is a front elevational view of the tool tray assembly of FIG. 1, the rear end elevational view being identical thereto;

FIG. 3 is a right end elevational view of the tool tray assembly of FIG. 1, the left end elevational view being identical thereto;

FIG. 4 is a top plan view of the tool tray assembly of FIG. 1;

FIG. 5 is an exploded perspective view of the tool tray assembly of FIG. 1, and showing a lid of one storage box pivoted upward to an open position;

FIG. 6 is a top plan view of the tool tray of the tool tray assembly of FIG. 1 with the storage boxes removed therefrom;

FIG. 7 is a bottom plan view of the tool tray of FIG. 6;

FIG. 8 is a front elevational view of the tool tray of FIG. 6, the rear end elevational view being identical thereto;

FIG. 9 is a right end elevational view of the tool tray of FIG. 6, the left end elevational view being identical thereto;

FIG. 10 is a top plan view of one of the storage boxes of the tool tray assembly of FIG. 1, the other storage box being identical thereto;

FIG. 11 is bottom plan view of the storage box of FIG. 10;

FIG. 12 is a front elevational view of the storage box of FIG. 10;

FIG. 13 is a rear elevational view of the storage box of FIG. 10; and,

FIG. 14 is a right end elevational view of the storage box of FIG. 10, the left end elevational view being a mirror image thereof.
